CLAIM

The ornamental design for a chair, as shown and described.

DESCRIPTION

FIG. 1 is a perspective view of my chair showing my new design;

FIG. 2 is a front view thereof;

FIG. 3 is a right side view, the left side view being a mirror image thereof;

FIG. 4 is a top plan view thereof;

FIG. 5 is a rear plan view thereof; and

FIG. 6 is a bottom view.

The inventive design is characterized by the incorporation of arm rests in the form of independent rectangular panels with rounded edges, as well as the size and positioning of the panels with respect to legs, a back and seat as shown.
